UNITED STATES PATENT OFFICE

2,168,044

INCINERATOR FURNACE

Leo Paul O'Hara, Pittsburgh, Pa.

Application March 4, 1938, Serial No. 193,892

5 Claims. (Cl. 110—18)

My invention relates to incinerator furnaces, and more particularly to those of the domestic type as for residences, apartment buildings, hotels and other buildings.

5 The following are among the novel characteristic features of my invention:

I provide a compact and efficient furnace of simple construction which occupies a minimum of space but is fully efficient.

10 I provide for the efficient elimination of smoke and fumes.

I provide a new and improved grate structure which may be installed and replaced without disturbing the brickwork of the furnace.

15 I provide a new and improved burner and draft structure which is of simple and durable construction and which enables the burner to operate without clogging although the material to be consumed may be packed tightly in the combustion chamber, and which enables the flame to successfully attack the material.

20 I provide a new and improved door structure which prevents the loosening of the door casings in the brickwork.

25 Other novel features of construction and also of arrangement of parts will appear from the following description:

Referring to the drawings, wherein I have illustrated a practical embodiment of the principles 30 of my invention,

Fig. 1 is a vertical section taken through the incinerator and its stack in a plane at right angles to the plane of the feed door.

Fig. 2 is a horizontal section, on enlarged scale, 35 taken along the line 2—2 of Fig. 1.

Fig. 3 is a broken enlarged vertical section taken along the line 3—3 in Fig. 1.

Fig. 4 is an enlarged perspective of the burner block, the burner and the by-pass assembly.

40 Fig. 5 is a broken side elevation of the same.

Fig. 6 is a perspective of one of the grate supporting bars.

Fig. 7 is a top plan view of the burner.

Fig. 8 is a side elevation of the same.

45 Fig. 9 is an end view of the burner looking from the left in Figs. 7 and 8.

Fig. 10 is a perspective showing the inner face of the front plate.

Fig. 11 is an end view looking from the right in 50 Figs. 7 and 8.

Referring to the drawings, the furnace is preferably of rectangular or cross-sectional shape having a front wall 1, rear wall 2 and side walls 3. The outer portion of said walls are preferably of building brick with an inner lining of refractory

brick as illustrated at 1^a, 2^a and 3^a. Above the combustion chamber 4 the front and side walls are corbeled in as at 5 to reduce the inner dimensions of the furnace to those of the stack 6. 7 represents a strengthening bar or bars embedded in the brickwork to reinforce the structure.

The corbeling in produces a plurality of horizontal surfaces or slopes which tend to baffle the ascending gases and facilitates their combustion.

The stack is extended upwardly through the roof of the building and is provided at its top with 10 a suitable screened spark-arrester 8.

The stack is provided at one or more of the floors of the building with a suitable hopper-door 9 for the introduction of material into the furnace for burning.

The front wall of the combustion chamber, above the grates, later described, is provided with a door opening 10 for the introduction of material and for general access to the combustion chamber.

15 11 represents a cast anchor plate of sufficient length to horizontally bridge the top of the opening 10 in the inner wall 1^a and to have its ends embedded in the brickwork at either side of the opening. To reduce the weight of this casting, and to facilitate its bonding with the brickwork, the plate is provided with a plurality of openings 12, and its perimetral edge is provided with a beading 13 which strengthens the plates and also assists in anchoring it in place.

20 The mortar will enter the openings 12 and form anchoring necks which will effectually prevent the loosening of the plate relative to the brickwork.

25 The front edge of the plate 11 is provided with two or more horizontal extensions 14 which extend forwardly into the opening in the outer wall of the opening 10 and overlap from above the top wall of the square cast door casing 15 to which the door 16 is hinged. The top wall of the box 15 and the extensions 14 are provided with registering holes through which cotter pins 17 or other members are inserted to anchor the door casing 15 to the plate 11.

30 It is evident that the door 16 and its casing 15 are thus securely anchored in place and that the expansion and contraction of the brickwork, in response to changes of temperature, will not loosen the door structure from its place in the brickwork of the combustion chamber.

35 Beneath the grates the front wall of the combustion chamber is provided with the ash-removal and clean-out opening 18 and door 19. The casing of the doorway 18 is anchored in

place by a plate 11 similar to that described above. Spanning the combustion chamber from front to rear are a pair of grate-supporting bars 20 and 21. The rear ends of said bars are provided with registering holes through which extend the through-bolt 22 having threaded ends with nuts 23 screwed up thereon against either face of the bars, thus holding the bars in proper spaced relation. The ends of the bars and the bolt 22 are embedded in the brickwork 2a as illustrated in Fig. 2. The front end of the bar 21 is embedded in the brickwork of the front of the combustion chamber and extends flush with the exterior thereof, while the front end of the bar 20, which is formed as shown at the right in Fig. 6, protrudes through the front wall of the furnace and is provided with the angular extension 24 for the attachment of the shaker lever 25.

Intermediate of their extent in the combustion chamber the bars 20 and 21 are provided with means for pivotally supporting the dump grate 26, which is of the proper width to fit between the bars 20 and 21 and is of proper length to fit the combustion chamber. The grate 26 is provided at the center of each side with a trunnion 27, one of which fits in a bearing hole in the bar 21 while the other trunnion fits in a bearing 28 in the bar 20, the bearing 28 being open at its top for the ready mounting and dismounting of the shaker grate 26.

Adjacent its rear each bar is provided on its inner surface with a lug 29 forming an abutment to stop or support the rear end of the grate 26 when the latter is horizontal.

In advance of its trunnions on one side the grate 26 is provided with a depending arm 30 pressed for connection to the inner end of the link 31, which extends forwardly along the inner face of the bar 20 without the furnace where it is pivotally connected to the lower end of the shaker lever 25 below the pivotal connection of said lever with the projection 24 of the bar 20. Thus the grate may be shaken from without the furnace.

To protect the link 31 from being fixed in position by mortar or cement when the furnace is being built, and from being obstructed by material during operation, I provide the inner face of the bar 20 with horizontal spaced flanges 32 between which the link 31 slides and 33, shown in Fig. 3, is a piece of sheet metal, which is bent at right angles to be held between the bottom 55 of the bar 20 and the brickwork, and which is folded up in front of the flanges 32 and has a reduced upper end inserted in a slot 33a in the bar.

The outer faces of the bars 20 and 21 within the combustion chamber are provided with sockets 34 at spaces at equal distances from the bearings of the shaker grate, in which are stepped the depending projections 35 on the lower edges of the inclined side grates 36. These projections 65 are slightly angular to the planes of the side grates so that the latter are held in their inclined positions shown in Fig. 3. The tops of the sockets 34 are slightly below the top edges of the bars 20 and 21, so that when the grates 70 36 are in place, their lower extremities bear inwardly against the outer faces of the bar, thus supporting the grates in position. The upper ends of the grates 36 rest against the side walls of the furnace, as shown in Fig. 3.

The doorway 10 and the grates 26 and 36 are

of the proper relative dimensions that they may be inserted and removed and also mounted in and dismounted from place, through the doorway.

37 represents the cast burner block which is 5 built into the brickwork at the front of the furnace and is provided with a vertical front end wall 38 having a circular hole 39 for the insertion of the burner 40. 41 represents the vertical side walls of the block between which the 10 burner extends. The side walls are arched upwardly to save metal and have their bottom edges provided with outwardly extending flanges 42 which aid in anchoring the block in the brickwork. 43 represents vertical outwardly extending 15 flanges at the inner ends of the walls 41 which bear against the inner surface of the wall 1a at either side to hold the block against outward movement.

The upper portion of the block is provided 20 with an inwardly extending nose or projection 44 which forms a shield to prevent the material from being packed immediately in front of the burner where it would obstruct the operation of the latter. The under surface of the shield 25 44 is horizontal and sufficiently spaced above the flame to avoid interference. The upper surface of the shield is inwardly and downwardly inclined so that material will not lodge thereon.

The shield 44 is chambered as at 45 for cooling 30 the same and air is admitted thereto by the duct 46 formed on the block 37 and extending from without the furnace. At either side a port 47 in the end of the chamber is positioned close to the inner surface of the front wall of 35 the furnace and along the inner vertical wall of the port is a vertical flange 48.

49 represents the flue member, the lower portion of which is bifurcated to form two curved legs 50 which straddle the burner box as illustrated in Figs. 3 and 4. The upper portion is a straight stem 51. The outer edges of the legs and the lower stem are provided with an edge flange 52 which when the flue member is in position bear against the inner surface of the furnace wall 45 thus forming two upwardly conveying flues. The outer surface of each of the legs 50 adjacent their lower ends are provided with two wedge lugs 53 which when the flue member is pushed downwardly along the furnace wall into the position 50 illustrated in Figs. 3 and 4 are wedged against the inner surfaces of the flanges 48 of the block and thus support the flue member 49 fixedly, yet removably, in place, with the flues formed by the legs and the furnace wall communicating at their lower ends with the ports 47 and also at their lower extremities with the interior of the furnace adjacent and at either side of the burner. The ribs 52 stop short of the upper end of the stem 51 to provide for the lateral escape of air 60 into the furnace. The upper extremity of the stem 51 is inclined into contact with the furnace wall and is stiffened by the central longitudinal rib 54.

Thus secondary air is admitted to the burner 65 flame from the chamber 45 and in case the material is packed so tightly above the grates to materially impede combustion of the material, the products of combustion may in part escape upwardly through the flues of the member 49 and 70 escape into the upper part of the combustion chamber thus maintaining combustion until the fire eats into the mass of material in front of the burner.

55 represents a face plate fastened to the front 75

of the furnace against the burner block 37 and overlapping the brickwork. The plate is provided with an opening for the burner 40 and also for the link 31. The plate also is provided with a notch 24^a to provide clearance for the end 24 of the bar 20 and a slot 31^a for the link 31. The face plate 55 is provided in its inner face with the horizontal rib 55^a to support the burner block and with vertical ribs 55^b to engage either side thereto to hold the block against movement. The plate is held in place by screws extending through holes 55^c in the plate and engaging threaded holes in the ends of the bars 20 and 21. The outer end of the duct 46 is above the top edge of the plate 55.

The burner 40 is of the tubular type having at its outer end a bell shaped air-mixer 56 having a diametric cross bar 57 provided with a threaded hole for connecting the gas supply pipe. Inwardly from the mixer 56 is a circular head 58 which fits up against the plate 55 overlapping the hole therein, and is secured thereto by means of screws engaging the notches 59 in the flanged and threaded holes in the plate. The head 58 is provided with arcuate concentric air openings 59^a, preferably screened for the admission of air along the burner into the furnace.

60 represents a pilot passage cast integrally with the mixer bell and extending through the head 58, the outer end of the passage being threaded for connecting the gas supply for the pilot light. The inner end of the passage opens through the head 58. Means are provided for lighting the pilot light at the inner end of the passage 60. Thus I have shown a cut sawn through the wall of the passage 60 and the wall of the adjacent arcuate opening 59^a through which sufficient gas will flow to enable the pilot to be lit with a match. The screens in the openings 59^a will prevent material or dangerous back firing of the flames and a notch 59^b in the screen permits the flame to travel to the pilot when a match is applied. There may occur a slight back firing through the notch 59^b in the screen but the same 45 is not sufficient to be injurious or dangerous.

The inner end of the burner is what I term a "duck-bill", being flattened out laterally to provide a narrow horizontal emission slot 61 from beneath which extends a horizontal lip 62 which 50 is stepped down below the slot 61, as shown at 63.

The lip 62 prevents drafts from below from blowing out the burner flame. If the lip were not stepped down below the slot, the flame would 55 be in advance of the free end of the lip and thus would be readily blown out. However, by stepping the lip downwardly below the slot, I position the flame nearer the slot and above the lip, so that the flame cannot be blown out.

60 I claim:

1. In an incinerator furnace, a burner assembly comprising a burner block arranged to extend through the wall of the combustion chamber, a tubular gas burner extending through the block, a shield above the inner end of the burner, said

shield being chambered, means for supplying air to said shield from without the furnace, and a draft flue communicating with the interior of the shield and extending upwardly within the furnace.

2. In an incinerator furnace, a burner assembly comprising a burner block arranged to extend through the wall of the combustion chamber, a tubular gas burner extending through the block, a shield above the inner end of the burner, said shield being chambered, means for supplying air to said shield from without the furnace, a port in the wall of the shield to admit air adjacent the inner end of the burner, and a draft flue having its inlet adjacent the inner end of the burner and extending upwardly within the combustion chamber.

3. In an incinerator furnace, a burner block arranged to extend through the wall of the combustion chamber, a tubular gas burner extending through the block, a chambered shield extending over the inner end of the burner, means for supplying air to the shield from without the furnace, the shield having ports at either side for the emission of air, a flue extending upwardly within the furnace and having a bifurcated lower portion straddling the shield and having inlet openings adjacent said ports.

4. In a burner assembly for use with an incinerator furnace provided with a grate, the combination of a burner block arranged to extend through the wall of the furnace, a shield projecting into the interior of the furnace from the inner end of the burner block above and closely adjacent the grate, said shield being chambered, a tubular burner extending horizontally through the burner block and having its inner end positioned above the grate and beneath the shield, a passage through the burner block for introducing air from without the furnace into the interior of the shield, and means adjacent the inner end of the burner for the escape of air from the interior of the shield into the interior of the furnace.

5. In a gas burner the combination of a tubular body having an inlet opening at one end and a burner tip at the other end, a wall integral with and radial to the tubular body intermediate the ends thereof, a longitudinal enlargement formed integral with the tubular body and extending through said wall with its inner end stopping short of the burner tip, a screened aperture in said wall adjacent said enlargement, a passageway enclosed within said enlargement for carrying fuel from the inlet opening of the tubular body to the inner end of the enlargement, means defining a slot through the wall of the enlargement into said passageway and extending from its inner end to a point beyond the wall, and means defining a small aperture in the screen in register with said slot, to permit the ignition of the gas at the inner end of the passageway by the application of a match to the slot at a point beyond the wall.
